W. F. RITTMAN,
TREATMENT OF HYDROCARBONS,
APPLICATION FILED FEB. 5, 1917.

1,419,122.

Patented June 6, 1922.

UNITED STATES PATENT OFFICE.

WALTER F. RITTMAN, OF PITTSBURGH, PENNSYLVANIA, ASSIGNOR TO SYNTHETIC HYDROCARBON COMPANY, OF PITTSBURGH, PENNSYLVANIA, A CORPORATION OF DELAWARE.

TREATMENT OF HYDROCARBONS.

1,419,122.

Specification of Letters Patent. Patented June 6, 1922.

Application filed February 5, 1917. Serial No. 146,720.

To all whom it may concern:

Be it known that I, WALTER F. RITTMAN, residing at Pittsburgh, in the county of Allegheny and State of Pennsylvania, a citizen 5 of the United States, have invented or discovered certain new and useful Improvements in the Treatment of Hydrocarbons, of which improvement the following is a specification.

- 10 In the practice of the vapor phase cracking process described and claimed in application Serial Number 29020, filed May 18, 1915, (as fully described in Dept. of the Interior Bulletin No. 114) wherein oil in a 15 gaseous condition is subjected to combinations of time, temperature and pressure, dependent upon the end product desired, when reducing high boiling hydrocarbons to lower boiling hydrocarbons, it has been found that 20 important results can be attained by effecting a partial cracking of the hydrocarbons while they are in a liquid state or condition and then discharging the partially cracked materials into a retort where substantially 25 complete vaporization will be effected, substantially instantaneously, the vapors heated to, or approximately to, a cracking temperature, and then subjected to sufficient heat to complete the cracking initiated while 30 the material was in a liquid condition. While thus subjecting the material to progressive cracking, the reactions will occur with less violence, and it is believed with the 35 formation of a relatively smaller percentage of undesirable end products.

The invention herein described, has for its object the cracking of petroleum hydrocarbons in two states or conditions; first, in a liquid state under pressure, which may be 40 less than, equal to, or greater than that maintained while carrying out the second stage, which is effected by vaporizing the liquid and subjecting it while in such vaporous condition, to a temperature of at least 400° 45 C. and a pressure above atmospheric and preferably in excess of 30 lbs. per square inch.

In cracking the material while in a liquid condition, which is preferably carried out 50 in a comparatively small tube, the oil is preferably subjected to a lower temperature than that maintained in effecting the final cracking after the hydrocarbons have been vaporized. As an organic reaction, the 55 cracking of petroleum is a direct function

of the time during which it is subjected to a given temperature; the results produced by applying to the material a high temperature for a short time are comparable with those produced with the application of a 6 lower temperature for a longer time. Hence the cracking of a material in a liquid condition may be effected in a short tube if a high heat be applied thereto, or in a longer tube subjected to a lower heat, the rate of 65 flow being the same in both cases. The final cracking after the material has been vaporized, is preferably effected in a form of apparatus permitting the vapors to flow continuously downward in a column while subjected to suitable pressure and to sufficient heat to first raise the vapors to cracking 70 temperature and then to a greater heat to effect the cracking.

To attain commercial conditions, it is generally desirable that oil should be treated at a rate of at least 100 gallons per hour, and as it is desirable to effect the cracking of a considerable portion of the material while in a liquid condition, the liquid should 80 be heated to a temperature substantially higher than its boiling point, thus necessitating the application to the liquid of pressure which will generally be above that in the retort, but may be higher than that desired in effecting the final and complete 85 cracking, and hence provision should be made for maintaining different pressures in carrying out the two operations. The pressure applied to the liquid can be controlled 90 by proper regulation of the rate of feed of the liquid into, and its discharge from the tube, wherein it is subjected to the desired heat; and the pressure in the retort can be controlled by regulating the discharge vapors from the retort, relative to the flow of liquid from the tube into the retort. The invention is hereinafter more fully described 95 and claimed.

In the accompanying drawings forming a 100 part of this specification, Fig. 1 is a view partly in side elevation and partly in section, showing a form of apparatus adapted for the practice of the invention described herein; Fig. 2 is a similar view of a modification of the apparatus.

In the practice of the invention, the retort 1 is arranged in a substantially vertical position within a suitably heated furnace adapted to raise the temperature of the va- 110

pors within the retort, to a cracking temperature as described in application Serial Number 829,169, filed April 3rd, 1914, and application Serial Number 85,603 filed 5 March 24th, 1916. A tube 3 extends through the bottom of the retort to a suitable point adjacent to the top where it is provided with outlets into the retort. Suitable provision is made for forcing oil into the lower 10 end of the tube, as for example, by enclosing a portion of the tube outside the retort in a drum 4 into which oil is forced by a pump 5, the oil flowing from the drum through perforations in the tube and thence 15 up and along the same to the outlets near its upper end.

In the operation of treating oil, the latter is caused to flow up through the tube and while passing along the same, is subjected to the heat of the vapors contained 20 within the retort. By so regulating the rate of flow into the tube, relatively to the discharge from the upper end of the tube, the liquid may be placed under such pressure 25 as will permit of its being heated to a cracking temperature without substantially vaporizing the liquid. This cracking of the liquid will be proportionate to the main cracking in the retort in a manner characteristic 30 of my vapor phase process above referred to. The oil being vaporized as it is discharged into the retort, the vapors heated, to or approximately to, a cracking temperature and then finally cracked.

35 While it is preferred to employ a form of apparatus as shown in Fig. 1 and also described and claimed in application Serial Number 184232 filed Aug. 3, 1917, the heating and cracking of the oil while in a liquid 40 condition, and prior to its being fed into the retort, may be effected by any other suitable means or form of apparatus, such for example, as that shown in Fig. 2. In this construction of apparatus, the oil is fed 45 through a coil 8 to which heat is applied by any suitable form or construction of furnace, and then after being so heated the oil passes on up and is discharged into the upper end of the retort. The process of treating 50 the oil in the form of apparatus shown in Fig. 2 is identical with that shown in Fig. 1 except that the heat required for cracking the oil while in a liquid condition is obtained from a source independent of 55 that employed for cracking the vapors in the retort.

As before stated, the pressure in the retort may be independently regulated, and hence the process and apparatus described 60 for carrying it out, is adapted not only for the manufacture of liquid and products such

as benzene, toluene, etc., but also for gaseous products such as ethylene, etc., where the pressure in the retort, to give the best results, should be not greater than 10 pounds 65 absolute, as described and claimed in application Serial Number 829,169, filed April 3rd, 1914.

I claim herein as my invention:

1. The process herein described of changing the high boiling hydrocarbons to lower boiling condensable hydrocarbons which consists in subjecting the hydrocarbons while in a liquid condition to such temperature and pressure as to cause a substantial cracking of the liquid, vaporizing such liquid and subjecting the vapors in a vertically moving column to temperatures higher than that employed in the liquid cracking and pressure and for such a period of time as 80 will effect the formation of the desired low boiling condensable end product desired in substantially large quantities.

2. The process herein described of changing high boiling hydrocarbons to lower boiling condensable hydrocarbons which consists in subjecting a uniform mixture of hydrocarbons while in a liquid condition to such temperature and pressure as to cause a substantial cracking of the liquid, simultaneously vaporizing substantially all the components of such liquid thereby effecting a substantially uniform mixture and subjecting such mixture in a substantially vertical unobstructed chamber to such conditions of temperature and pressure for such a period of time as will effect the formation of the desired low boiling condensable end product in substantially large quantities.

3. The process herein described of changing the hydrocarbons having high boiling points to condensable hydrocarbons having lower boiling points which consists in passing the liquid hydrocarbons through a tube wherein it is subjected to such temperature and pressure as to cause a substantial cracking of the liquid, discharging the cracked hydrocarbon in a substantially vertical unobstructed tube of larger diameter than the first, effecting a completion of vaporization of substantially all the components of the hydrocarbon discharged into such second tube and subjecting the uniform mixture of vapors thus produced to such conditions of temperature and pressure and for such a period of time as will effect the formation of the desired lower boiling condensable end product in substantially large quantities.

In testimony whereof, I have hereunto set my hand.

WALTER F. RITTMAN.
